[57] CLAIM

The ornamental design for a chandelier, as shown and described.

DESCRIPTION

FIG. 1 is an elevational view of a chandelier, showing my new design;

FIG. 2 is a top plan view thereof;

FIG. 3 is a bottom plan view thereof; and,

FIG. 4 is an elevational view of an alternate embodiment of the chandelier of the present invention.

The top and bottom views of the second embodiment are substantially identical to those of the first embodiment, differing only by the additional configuration of the shades.
